(No Model.)

T. B. WEBSTER.
Car Brake and Starter.

No. 239,206.

Patented March 22, 1881.

UNITED STATES PATENT OFFICE.

THOMAS B. WEBSTER, OF ELIZABETHPORT, NEW JERSEY.

CAR BRAKE AND STARTER.

SPECIFICATION forming part of Letters Patent No. 239,206, dated March 22, 1881.

Application filed November 30, 1880. (No model.)

To all whom it may concern:

Be it known that I, THOMAS B. WEBSTER, of Elizabethport, in the county of Union and State of New Jersey, have invented certain new and useful Improvements in Car Brakes and Starters and in Clutches therefor, of which the following is a specification.

My invention is applicable, principally, to horse-cars for street-railways; and its object is to provide, in a simple and convenient manner, for storing up power derived from the momentum of the car when brakes are applied to stop it, and to effectively apply such power to aid in starting the car.

My invention consists in the combination, with the two axles of a car or car-truck, of a drum upon one axle, which may be locked fast thereto when the car is to be stopped, and by its rotation, acting through chains or other connections, rotates a drum loosely mounted upon the other axle of the car, and through other chains or connections attached to the last-mentioned drum compresses or applies tension to a spring or springs and stops the car. I employ, in connection with the last-mentioned drum, a clutch or clutches, which permit the drum to rotate freely on the axle while tension is applied to the spring or springs, but which prevent the drum from being rotated in the opposite direction by the resiliency of said spring or springs without imparting motion to the car-axle upon which it is mounted. Where two clutches are employed in connection with the last-mentioned drum they are arranged upon said axle so that one prevents the rotation of the axle independently of the drum in one direction, while the other prevents its rotation independently of the drum in the opposite direction, and I employ in connection with said drum and clutches novel means for rendering either one of said clutches inoperative, so as to provide for moving the car in either direction.

The invention also consists in a novel construction of clutch, which I use in carrying out my invention.

The invention also consists in various novel details of construction, to be hereinafter described.

In the accompanying drawings, Figure 1 represents a plan, partly in section, of the run-

ning-gear of a car having my improved devices connected therewith, and a dotted outline of the frame of the platform. Fig. 2 represents a longitudinal section thereof upon the dotted line *x x*, Fig. 1. Fig. 3 represents a portion of one of the axles and a central longitudinal section of the drum, which is connected by chains or other connections with the spring or springs. Fig. 4 represents a similar section at right angles to Fig. 3. Fig. 5 represents a transverse section upon the dotted line *y y*, Fig. 4; and Fig. 6 represents a similar section on the dotted line *z z*, Fig. 4.

Similar letters of reference designate corresponding parts in all the figures.

A designates the frame of a car-platform, and *B* and *C* designate, respectively, the front and rear axles, supported in suitable bearings attached to the frame, and having secured upon them wheels *C'*, the axles being adapted to rotate with the wheels.

Upon the front axle, *B*, is a clutch, consisting of a central female portion or drum, *D*, which is mounted loosely upon the axle *B*, and two male parts, *D'*, which are placed upon opposite sides of said central part or drum, *D*, and are secured to the axle by means of feathers, so as to rotate therewith, but also so that they are capable of longitudinal movement thereon. The parts *D'* are constructed with conical portions or projections *a*, adapted to enter correspondingly-shaped recesses in the part *D*, and, when the parts *D'* are moved toward each other, to lock the central part, *D*, fast to the axle, so as to rotate therewith. As shown in Fig. 1, the recesses in the part *D*, into which the projections *a* enter, are lined with wood, so as to prevent abrasion from iron working against iron.

E designates levers, pivoted at *b* to suitable supports depending from the car-platform, forked at one end to engage with grooves in the parts *D'*, and connected at the other end by toggle-links *E'* with a draw-bar, *E*. By this arrangement of levers, when the car is being drawn forward, the axle *B* rotates freely of the central part or drum, *D*.

Upon the axle *C* is loosely mounted a drum, *F*, which is divided into three annular recesses or grooves, *c c c'*. In the outer recesses or grooves, *c c*, are attached chains *d d'*, or simi-

lar flexible connections, which are wound once or more around the drum, and are thence passed one to the upper and the other to the under side of the drum D, and are wound thereon in opposite directions and attached at the ends thereto.

G designates bolts or rods, which project inward from the end of the car-frame A; and H designates spiral springs arranged upon said bolts, and fitting between the ends thereof and a cross-head, I, which is adapted to slide longitudinally thereon. To the cross-head I is attached a chain or other connection, e, which is wound around the drum F in an opposite direction to the chains d d', and in the central annular recess or groove, e', and has its end attached to said drum.

In lieu of the two springs G, a single spring, properly arranged, might be employed.

When it is desired to stop the car the draw-bar E is moved inward by the driver or conductor by any suitable means—as, for instance, by a brake-spindle, J, having an arm or toe, f, adapted to engage with a collar upon the draw-bar, and the inward movement of said draw-bar, acting through toggle-links E' and levers E, moves the parts D' nearer together and toward the part D, thereby locking said part firmly upon the axle, and causing it to rotate therewith. The turning of the drum D, acting through the chain d, passed around the upper side thereof, will rotate the drum F, and through the chain e will draw the cross-head I along the bolts or rods G and compress the springs H, which offer a rapidly-increasing resistance to the turning of the drums D and F, and finally stop the car. In some cases, where the car is not turned round at the end of the route, it will be necessary to be able to move the car in a reverse direction to that here indicated, and when the car is thus drawn the chain d', passed around the under side of the drum D, will act in the same manner as previously described to compress the springs H.

The brake should be always under control of the driver as well as the conductor; and to enable the driver to apply the brake when the car is drawn backward, I provide at the rear end of the car a second brake-spindle, J'. The two spindles J J' are provided with pulleys or wheels g g'; and g' g'' designate chains or other connections wound around and fixed to said pulleys, by pins or otherwise, and extending in opposite directions from each spindle around guide-pulleys g² g²'. The chains g' might extend the length of the car; but the chains which extend to the right and left of the spindles, after passing around the guide-pulleys g², are preferably connected by two small rods, g³.

When the horses are attached to the draw-bar E², the parts D' are made to engage with the drum D by the driver, but are disengaged from said drum to free it from the axle by the forward pull of the horses upon the draw-bar in starting the car. When, however, the horses are attached to what is here the rear of the

car, the driver not only moves the draw-bar inward to lock the drum D to the axle, but he must also move it in the opposite direction to release said drum from the axle.

So far as described the mechanism for stopping the car is complete; but in order to apply the power of the springs H, it is necessary that the drum F be locked fast to the axle C when turned in the opposite direction to that in which it is turned to compress said springs.

As the drum F may be turned to compress the springs by the turning of the drum D in either direction incident to the movement of the car in either direction, it is obvious that when the car is moving forward the drum F should be locked fast to the axle C when turned in the direction indicated by the arrow, Fig. 1, and turn free in the opposite direction, while when the car is moved backward the drum F should turn free of the axle when turned in the direction indicated by said arrow, and be locked fast thereto when turned in the opposite direction. This is effected by means of a clutch of any suitable character at each end of the drum F, and mechanism for rendering either clutch inoperative at the pleasure of the driver or conductor. For this purpose I prefer to use a peculiar construction of clutch. (Shown best in Figs. 3, 4, 5, and 6.)

The drum F, which, as before stated, is loosely mounted upon the axle C, is constructed at each end so as to form parts of two clutches, the other parts, F' F², of which are made fast to the axle, so as to rotate therewith. The connection between the parts F' and F is such that the former may turn free of the latter in one direction, and the connection between the parts F² and F is such that the former may turn free of the latter in the other direction. The drum F has in its ends annular spaces h h', while the parts F' and F² have each a lip or rim, i, adapted to slip over the drum F and hold the three parts concentrically.

K K' K' designate dogs, of which a pair, K K, are arranged between the parts F' and F, and a pair, K' K', between the parts F² and F, and which are provided with projections j, fitting in the annular spaces h and h', and the form of which is shown in dotted outline in Figs. 5 and 6. Upon the inner face of each part F' and F² are two lugs, k, opposite each other, and adapted to engage with the faces of the dogs at opposite points, l. The only difference in the connection between the parts F' and F and the parts F² and F is that the dogs K in one case are arranged directly opposite to the arrangement of the dogs K' in the other case, as seen by a comparison of Figs. 5 and 6. Although the arrows in Figs. 5 and 6 point in opposite directions, they really indicate the movement of the drum F in the same direction, as said figures show opposite ends of the said drum. When the drum F is turned in the direction indicated by the arrow, Fig. 5, it will turn freely of the part F'; but when turned in the opposite direction by

- the force of the springs H the outer side of the annular space h will bite upon the edges of the projections j at j' , and forcing the opposite angle of said projections against the inner side of said annular space and locking the dogs will cause them both to move with said drum, and by the faces l of said dogs engaging with the lugs k upon the part F' , said part, with the axle C , will be turned and the car impelled forward. When the drum F is turned in the direction of the arrow, Figs. 5 and 6, the dogs K' between it and the part F^2 (see Fig. 6) will be locked in the annular space h' , in the manner just described with reference to the dogs K , and will, by the faces l of the dogs K' bearing against the lugs k on the part F^2 , turn said part, and with it the axle, while when turned in the opposite direction the drum F will turn free of the part F^2 .
- When the car is to be moved forward the clutch-connection between the drum F and the part F^2 is to be rendered inoperative, while when the car is to be moved backward the similar connection between the drum F and the part F' is to be rendered inoperative. This I effect by means of two flanges or collars, $L' L^2$, mounted loosely on the hubs of the parts F' and F^2 , and adapted to be shifted longitudinally of the axle C by means of forks $n n$ engaging with grooves therein and actuated by levers $M' M^2$. The flanges or collars $L' L^2$ carry pins or projections o , which are inclined upon their inner sides, and by the movement of the flanges or collars inward are inserted through holes in the parts $F' F^2$ outside the dogs $K K'$, and by their inclined inner sides bearing upon said dogs the dogs of each pair are moved toward each other, which prevents the annular spaces $h h'$ from locking the dogs when the drum F is turned in either direction. When both flanges or collars $L' L^2$ are moved inward to render both clutches inoperative, the drum F is entirely free, and cannot transmit the power of the springs H to turn the axle C . When the flange or collar L' is moved inward, the car is adapted for moving backward, and when the flange or collar L^2 is moved inward, as seen in Figs. 1 and 4, the car is adapted to move forward. When both flanges or collars $L' L^2$ are moved outward, both clutches are operative and the drum locked fast to the axle C .
- Where the car is intended to be turned round at the end of each trip, the part F^2 is dispensed with, and in such case no means are employed for rendering the clutch-connection between the drum F and the part F' inoperative, and in place of the chains $d d'$ only one chain is necessary.
- Though I have only represented this form of clutch as applicable to my invention, it may be employed for any other purpose to which it is adapted, and when so employed, although the part F might not be a drum, as here shown, it would in all cases be loose upon an axle or shaft, while the part F' would be fast thereon.

The spring or springs, instead of having tension applied by compressing them, might be distended or elongated in stopping the car, and exercise their power while returning to 70 their normal length.

Although my invention is shown in connection with a car having two axles, it is applicable to a car-truck having two axles and pairs of wheels. 75

If desirable, the bolts or rods G , upon which are the springs H , might have a swivel attachment with the car-frame, as shown dotted in Fig. 2, so as to be free to adjust themselves in line with the upper or lower periphery of the 80 drum F , to permit of the chain e pulling in a direct line with the bolts G , whether the car is moving ahead or backward.

It will be observed that the force of the springs in braking the car is all exerted upon 85 the front axle, B , and that the power of said springs in starting the car is all exerted upon the rear axle, C . In case the load were principally over the axle C , the wheels of the axle B might slip upon the track without effectively 90 stopping the car, and in case the load were principally over the axle B the axle C , when impelled forward by the springs, might not act effectively in starting the car. To obviate both of these difficulties, I prefer to connect 95 the two axles so that one cannot turn independently of the other, and this may be conveniently done by one or two chain-wheels, p , fixed to each axle, and a chain or chains, p' , from one wheel to the other, as shown in 100 dotted outline in Fig. 1.

I am aware that a car braking and starting apparatus has been devised in which the two axles of a car are constructed with square portions and comprising four drums, two of which 105 are shifted upon said square portions to put tension upon springs to brake the car, and the others of which are then shifted upon said square portions, to enable the springs to exert their power in starting, the two first-mentioned drums being simultaneously removed from said square portions. Such apparatus can, however, only be employed to bring the car to a full stop, as the drums are locked fast to the axle, and there is no chance for slip, and therefore separate braking mechanism must be employed for checking the speed of the car on downgrades when it is not desired to come to a full stop. Another objection to such apparatus is, that it requires a special construction 110 of car-axle, and cannot be readily applied to any car, as can mine. 115

I am also aware that it is old to combine with each of two car-axles two drums, one of which may be locked fast to the axle for the 120 purpose of compressing springs, and the other of which may be locked fast to the axle for applying the power of the springs to turn the axle. 125

I do not claim either of the above-described 130 mechanisms as of my invention, and in both of them it is necessary, after tension is applied to

the springs, to employ devices for holding the springs, while the drums through which tension is applied to them are released from the axles, and the drums through which their power is transmitted are locked fast to the axles. In my case no such holding devices are necessary, for as soon as the horses start ahead and exert a pull on the draw-bar (the clutch-connection through which the springs transmit their power to the axle being of such a nature that the said drum is automatically locked fast to the axle) the springs at once exert their power upon the axle.

What I claim as my invention, and desire to secure by Letters Patent, is—

1. The combination, with the two axles of a car or car-truck, of a drum mounted loosely upon one axle, a clutch for locking said drum fast to said axle, a draw-bar connected with said clutch, and means for moving said draw-bar inward to disengage the said drum from said axle, a drum mounted loosely upon the other axle, a spring or springs, and chains or other connections wound upon the last-mentioned drum in opposite directions, and connected, one with said spring or springs and the other with the first-mentioned drum, substantially as and for the purpose specified.
2. The combination, with the axles B, of the drum D, the clutch portions D', the levers E, toggle-links E', and draw-bar E², all substantially as specified.
3. The combination, with the axle B, of the drum D, the clutch portions D', the levers E, toggle-links E', draw-bar E², and the brake-spindles J J' at opposite ends of the car, connected with said draw-bar for moving it inward, all substantially as specified.
4. The combination, with the axles B and C, of a drum, D, on the axle B, a drum, F, loosely mounted on the axle C, the parts F' F², fixed

to the axle C, a clutch-connection between the drum F and part F', for preventing the drum from turning independently of said axle in one direction only, and a similar connection between the drum F and part F², for preventing the drum from turning independently of said axle in the other direction only, means for rendering either clutch-connection inoperative, a spring or springs, and chains or other connections, d, d', and e, all arranged substantially as and for the purpose specified.

5. The combination, in a clutch, of a part, F, having in its face an annular space, h, a part, F', having upon its face lugs k, and dogs K K, arranged between said parts and on opposite sides of said lugs k, and having projections j, engaging with said annular space, substantially as and for the purpose specified.

6. The combination of the axle C, drum F, having in its ends annular spaces h h', the parts F' F², pairs of dogs K K K' K', having projections j, for fitting in said annular spaces, flanges or collars L' L², movable longitudinally upon the axle, and provided with pins or projections o, whereby the dogs of each pair are moved toward each other as said flanges or collars are moved inward, substantially as specified.

7. The combination, with the two car-axles, 70 the drum D and clutch portions D' upon one axle, the drum F and parts F' F², each having a clutch-connection with the drum F, upon the other axle, a spring or springs, and the connections d d' e, of chain-wheels p upon said 75 axles, and one or more endless chains or bands passing over said wheels and connecting said axles, substantially as specified.
